ATTORNEY

UNITED STATES PATENT OFFICE.

JOBBY BELPEDIO, OF BRIDGEPORT, CONNECTICUT.

CUSHION HEEL.

Application filed September 18, 1925. Serial No. 57,047.

The present invention relates to improvements in cushion heels, and has for an object to provide a cushion heel, formed of rubber or the like, of relatively great resiliency, which at the same time is of sufficient hardness and wear resisting quality as to provide a substantial heel support adapted to maintain its original shape over a relatively long period of use, and in which deterioration due to wearing out of the rubber is reduced to a minimum.

A further object is to provide a cushion heel having a high resiliency cushioning element or means, combined with a ground gripping tread in the nature of a vacuum cup, adapted to cooperate with the cushioning element in such manner that as the same is compressed the tread is gripped with the ground to effectually resist slippage. A still further object is to provide a cushion heel including air cushion means adapted to provide more resilient cushioning, and which is so arranged that internal collapse or edge separation of the cushion heel from the leather heel is prevented.

It is proposed in the present embodiment of the invention to provide a rubber heel provided with an interiorly disposed cushioning area at the inner or non-tread side of relatively great resiliency, and a tread surface of wear resisting consistency including means adapted when pressure is applied to the heel to compress the cushioning area, and further to provide such means in the form of a vacuum cup for the purpose of forming a ground gripping element to prevent slippage.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a perspective view of the upper side of a cushion heel, according to the present embodiment of the invention;

Fig. 2 is a perspective view of the lower or tread side thereof;

Fig. 3 is a longitudinal sectional view of the same;

Fig. 4 is a longitudinal sectional view thereof, showing it attached to a shoe, and in compressed relation;

Fig. 5 is a plan view of the upper side of a cushion heel, according to a modified form 55 of the invention;

Fig. 6 is a longitudinal sectional view of the same; and

Fig. 7 is a longitudinal sectional view thereof, showing it attached to a shoe, and in 60 compressed relation.

Similar reference characters indicate corresponding parts throughout the several figures of the drawings.

Referring to the drawings, and more particularly to Figs. 1 to 4 thereof, the embodiment of the invention shown therein comprises a resilient heel body 10 formed of rubber of such consistency as to be wear resisting and of sufficient resilience as to provide a 70 cushioning tread or ground gripping surface. A series of nail receiving holes 11 is provided in inwardly spaced relation to the periphery, the holes being provided with countersink portions 12 and annular bosses 75 13 surrounding the portions 12.

Upon the upper side of the heel body, and in inwardly spaced relation to its periphery, there is provided a circular walled recess 14, and within this recess, and in inwardly 80 spaced concentric relation to its wall, there is provided a circular cushioning element 15 of relatively softer rubber than the heel body, as sponge or crepe rubber, and which is homogeneously joined to the heel body by vulcanizing or the like. The upper surface of the cushioning element is flush with the upper surface of the heel body, and the annular space 16 about the same forms an air pocket, which in the use of the heel functions as an 90 air cushion.

The tread surface of the heel body is provided in co-axial relation with the cushioning element with a dome-shaped circular boss 17, of substantially smaller diameter than 95 the cushioning element, and projecting with respect to the tread surface, and in annularly spaced relation thereto there is formed a rounded circular rib 18, projecting from the tread surface to a slightly less degree 100 than the boss 17, the inner diameter of the rib being less than that of the cushioning element, while the outer diameter is greater than that of the circular wall of the recess 14, so that said rib is substantially opposed beneath 105 the circular air cushion space 16.

The heel is attached to the leather heel portion 19 of the shoe by means of nails 20, and in such attached relation the soft interior cushioning area insures a constantly tight engagement at the edge between the rubber and the leather heels.

In Fig. 4 the heel is shown in its compressed ground engaging relation, the weight of the wearer being imposed thereon. In this relation the cushioning element is compressed through engagement of the boss 17 with the ground, and during such compression the annular rib 18 engages the ground in a manner as to produce a vacuum gripping contact therewith. As the heel is lifted from the ground it assumes the normal shape shown in Fig. 3. While the vacuum cup gripping effect provided by the rib 18 is sufficient to prevent slipping, the projecting boss 17 tends to break the vacuum as the heel is lifted, so that any tendency of the heel to stick and thereby impair walking is prevented. It will be seen that a high resiliency cushioning effect is produced, and at the same time the body of the heel is such that a substantial support is afforded which is wear resisting to a high degree, the cushioning inner tread surface provided by the boss 17 and rib 18 furthermore relieving the edge portion of the heel from considerable wear.

In Figs. 5 to 7 there is illustrated a modified form of the invention in which the cushioning element consists of a circular portion 21 formed integrally with the heel body in concentric spaced relation within the recess 14, and provided with a circular concave recess 22 inwardly spaced from its outer edge to provide an air cushion pocket, which in conjunction with the air space 16 provides an air cushioning area supported against collapse by engagement of the portion 21 with the under surface of the leather heel portion 19. The construction renders the central area of greater resiliency than the peripheral portion, the central air cushion portion functioning in substantially the same manner as the soft rubber cushion element 15 of the first described embodiment.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:—

1. A cushion heel, comprising a resilient heel body of rubber having a tread surface, an upper surface, and a peripheral surface, said upper surface being provided with a recess in inwardly spaced relation to said peripheral surface, and a cushioning element also of rubber and of greater resiliency than said heel body disposed in said recess, and substantially integrally connected to the heel

body, said heel having a space in relation to said cushioning element into which said element expands in its compressed relation.

2. A cushion heel, comprising a resilient heel body having a tread surface, an upper surface, and a peripheral surface, said upper surface being provided with a recess in inwardly spaced relation to said peripheral surface, and a cushioning element of greater resiliency than said heel body having its upper surface substantially flush with the upper surface of said heel body disposed in said recess in inwardly spaced relation to the wall of said recess to form an air pocket surrounding said cushioning element, said cushioning element adapted to expand into said air pocket in its compressed relation.

3. A cushion heel, comprising a resilient heel body having a tread surface, an upper surface, and a peripheral surface, cushioning means of greater resiliency than said heel body within said heel in inwardly spaced relation to said peripheral surface, and projecting means on said tread surface in opposed relation to said cushioning means adapted upon pressure being applied against said tread surface to compress said cushioning means.

4. A cushion heel, comprising a resilient heel body having a tread surface, an upper surface, and a peripheral surface, cushioning means of greater resiliency than said heel body within said heel in inwardly spaced relation to said peripheral surface, a continuous projecting rib on said tread surface in inwardly spaced relation to said peripheral surface and surrounding an inner recessed area to form a vacuum cup, said rib being opposed to said cushioning means and adapted upon pressure being applied against said tread surface to simultaneously compress said cushioning means and form a vacuum grip with the ground surface.

5. A cushion heel, comprising a resilient heel body having a tread surface, an upper surface, and a peripheral surface, cushioning means of greater resiliency than said heel body within said heel in inwardly spaced relation to said peripheral surface, a continuous projecting rib on said tread surface in inwardly spaced relation to said peripheral surface and surrounding an inner recessed area to form a vacuum cup, a central boss within said recessed area projecting with respect to the projected plane of said rib, said boss being opposed to said cushioning means and adapted upon pressure being applied to said tread surface to compress said cushioning means, and said rib adapted to simultaneously form a vacuum grip with the ground.

6. A cushion heel, comprising a resilient rubber heel body having a tread surface, an inner surface, and a peripheral surface, said inner surface being provided with a recess in inwardly spaced relation to said peripheral

surface, a circular cushioning element of relatively softer rubber than said heel body secured in said recess in inwardly spaced relation to the peripheral wall thereof to form an air pocket about said cushioning element, the upper surface of said cushioning element being substantially flush with the upper surface of said heel body, and projecting means on

said tread surface in opposed relation to said cushioning element adapted upon pressure 10 being applied against said tread surface to compress said cushioning means.

Signed at Bridgeport, in the county of Fairfield, and State of Connecticut, this 17th day of September, 1925.

JOBBY BELPEDIO.
